HUMIDIFIER

Fred W. Stilwell, Chicago, Ill.

Application November 2, 1938, Serial No. 238,493

5 Claims. (CL 281—15)

My invention relates to humidifiers and is more particularly concerned with a humidifier adapted to be installed in an office, home, or similar environment.

5 The humidifiers now on the market for installation in homes and offices are objectionable in that they lack the necessary nicety of control, with the result that they provide over-humidification. A further and even more serious difficulty with present humidifiers of this type lies in the fact that they are apt to overflow and damage rugs, floors, plaster, wall paper, and other household and office furnishings and appointments.

15 A primary object of my invention is to overcome these difficulties of the prior art humidifiers.

Another object of my invention is to provide a humidifier having an evaporator providing a maximum evaporating surface with a minimum volume of water.

Another object of my invention is to provide a humidifier having an improved control mechanism whereby the humidification may be accurately and nicely controlled to provide exactly the degree of humidity desired.

Another object of my invention is to provide a humidifier having an improved control mechanism which will absolutely prevent overflow and resultant damage to floors, ceilings, walls and furnishings.

Another object of my invention is to provide a humidifier having an electric booster for increasing the temperature of the water in the evaporator.

Another object of my invention is to provide a humidifier which may also be used as a heater for increasing the temperature of the air in the room or building in which the humidifier is located.

Another object of my invention is to provide a neat, attractive, inexpensive, and compact humidifier for offices and dwellings.

Another object of my invention is to provide a humidifier which may be automatically controlled and which requires a minimum of servicing and attention.

Other objects and advantages will become apparent as the description proceeds.

50 In the drawings:

Figure 1 is a perspective view of a preferred embodiment of my invention;

Figure 2 is a transverse vertical section taken on the line 2—2 of Figure 1;

Figure 3 is an irregular section taken on the line 3—3 of Figure 2;

Figure 4 is a partial vertical section showing the control mechanism and is taken on the line 4—4 of Figure 3;

Figure 5 is a partial section showing the emergency control mechanism and is taken on the line 5—5 of Figure 4;

Figure 6 is a partial view of the regular control mechanism for maintaining the proper water level in the evaporator and is taken on the line 6—6 of Figure 4;

Figure 7 shows a detail of the emergency control mechanism and is taken on the irregular line 7—7 of Figure 4;

Figure 8 is a wiring diagram;

Figure 9 is a partial wiring diagram of a modified form of my invention;

Figure 10 is a top plan view of a modified form of my invention wherein I have provided a heating element for raising the room temperature, most of the top of the cabinet being removed to show the internal construction; and

Figure 11 is a partial vertical section of the modification of Figure 10 and is taken on the line 11—11 of Figure 10.

Referring to Figures 1 to 8 of the drawings, I have shown therein an embodiment of my invention comprising a cabinet indicated generally by the reference numeral 12 and comprising a base 14 mounted on adjustable feet 16 and a top 18 supported on the base 14. The cabinet is preferably made of sheet metal or other suitable material and may be provided with any attractive and suitable finish.

The evaporator indicated generally by the reference numeral 20 comprises a pan 22 having upwardly extending flanges 24 secured to the walls of the top 18 by bolts, welding, or other suitable securing means. This pan 22 has a depressed central portion 26 between edge portions 28 and 30. As most clearly shown in Figure 3, the pan 22 extends from one end of the cabinet 12 to a partition 32 which divides the top portion 18 of the cabinet into an evaporator compartment 34 and a control compartment 36, the partition 32 being located adjacent one end of the cabinet, so that the evaporator compartment 34 extends for almost the full length of the cabinet.

The evaporator pan 22 is adapted to contain water to the level indicated in Figure 2 and the depressed central portion 26 contains the heating pipes 38 which extend lengthwise of the pan 22, as most clearly shown in Figure 3, and cause the heating medium to flow back and forth length-

wise of the evaporator pan. These heating pipes 38 have an inlet 40 and an outlet 42 adapted to be connected with the steam or hot water pipes for heating the building in which my humidifier 5 is installed.

Where the heating pipes 38 are connected with a hot water heating system wherein the temperature of the hot water supply is insufficient to provide the desired amount of heat for the water 10 in the humidifying pan 22, I provide a heat booster in the form of an electrical heating element 44 located in the central depression 26 below the heating pipes 38, as most clearly indicated in Figure 2. Where the heat supplied to the water 15 in the evaporator pan 22 by means of the heating pipes 38 is sufficient, the electrical heater 44 may be dispensed with. In the drawings I have shown an electrical switch 46 mounted on the front of the cabinet for controlling the heater 20 44 whereby this heater may be turned on and off as desired and thus permit its use only when insufficient heat is supplied through the pipes 38 to give the desired amount of evaporation of water in the pan 22.

25 An important feature of my invention lies in the particular structure of the evaporator comprising the pan 22 and heating means therefor. It will be noted that this evaporator provides a surface which extends the full width of the cabinet 30 and substantially the full length thereof, thus providing a maximum surface for evaporation. This full surface is exposed to the circulation of air through the top portion 18 of the cabinet. This air enters through the inlet 48 35 at the back of the cabinet and after picking up the moisture evaporated from the surface of the water in the pan 22, the humidified air leaves the cabinet by way of the grille 50.

By referring to Figures 2 and 3, it will be noted 40 that the water level maintained by control mechanism to be hereinafter described, is such that only a thin film of water overlies the sides 28 and 30 of the evaporator pan 22 and that there is only a small amount of water in the depressed 45 central portion 26 of this pan, due to the fact that the greater portion of the volume of this central portion of the pan is occupied by the heating pipes 38. This is an important feature of my invention in that it makes possible accurate control of the humidity of the room in which 50 the unit is located. In order to further decrease the amount of water in the evaporator pan 22, I may fill most or all of the available space in the evaporator pan up to the level of the water 55 therein with copper shavings 52 or other suitable non-corrosive heat conducting material providing interstices which are filled by the water in the evaporator pan.

Water is supplied to the evaporator pan 22 by 60 way of a pipe 54 which is connected to the water pipes of the building in which the humidifier is installed. As best shown in Figure 4 this pipe 54 is provided with a normally opened valve 56 and a normally closed solenoid controlled valve 58. The regular water level control float 60 is located in a corner of the central portion 26 of the evaporator pan which is not occupied by the heating pipes 38 or the copper shavings 52. This float has a rod 62 extending through the opening 65 provided by a guide 64 attached to the partition 32. The upper end of the rod 62 is connected to one end of a lever 66 extending through the partition 32 and pivoted at 68 on a bracket 70 attached to the partition 32. The other end of the 70 lever 66 carries a mercury switch 72 which con-

trols the circuit containing the solenoid valve 58.

This solenoid valve 58 is normally closed, thereby cutting off the supply of water to the evaporator pan 22. When the water level in this pan drops below a predetermined level, the float 60 pulls downwardly on the right-hand end of the lever 66 as viewed in Figure 6 and shifts this lever about its pivot 68 so that the mercury in the bulb of the switch 72 closes a circuit between the switch contacts and thus closes the circuit 10 including the solenoid valve 58. The resultant energization of the solenoid control for this valve opens the valve and permits water to flow through the pipe 54 to the evaporator pan 22. When the water level in the evaporator pan 22 reaches the 15 desired maximum level, the float 60 shifts the lever 66 in the opposite direction, thereby opening the mercury switch 72 and thus cutting off the supply of current to the solenoid control of valve 58. This valve thereupon closes and cuts off the 20 supply of water to the evaporator pan.

One of the principal disadvantages with prior art humidifiers of this general type has been the failure of such control mechanism with resultant overflow and damage to walls, floors, plaster, and 25 furnishings. A feature of my invention lies in an emergency control mechanism which prevents such overflow in case of failure of the normal control mechanism.

I have illustrated my improved humidifier as 30 being provided with a large emergency float 74 which normally rests on the heating pipes 38. This float 74 is connected to one end of a lever 76 extending through the partition 32 and pivoted at 78 on a block 80 attached to this partition. The other end of the lever 76 is in the form of a trigger 82 engaged in the notch 84 of a lever 86. This engagement of the trigger 82 in the notch 84 prevents the lever 86 from rotating about its pivot 88 under the influence of 40 spring 90.

If the regular control mechanism operated by the float 60 should for any reason fail to cut off the supply of water and the water in the pan 22 should rise above the permissible maximum level, 45 the rising water would raise the emergency float 74, thus releasing the trigger 82 from the notch 84. The lever 86 would thereupon rotate about its pivot 88 under the pull of the spring 90. This lever 86 carries a pair of pins 92 adapted to engage opposite sides of the control arm 94 of valve 58 so that the pivotal movement of the lever 86 under the influence of spring 90 closes valve 58 and cuts off the supply of water to the evaporator pan 22. 55

The lever 86 also has a pin 96 extending through the U-shaped member 98 attached to the lower end of a switch control rod 100 pivotally attached to links 102 and 104 pivotally supported on brackets 106 and 108 respectively, 60 these brackets being attached to the partition 32. The switch control rod 100 carries a second U-shaped member 110 which embraces the trigger control 112 of switch 114 which cuts off the supply of current to the heating unit 44 and the 65 solenoid control valve 58.

I preferably provide my humidifier with automatic means for regulating the humidity in the room in which my humidifier is installed. This 70 automatic humidity control comprises a humidiostat 116 illustrated as mounted on the front of the cabinet just above the electrical heating element control switch 46. This humidiostat controls a relay 118 in series with the solenoid controlled valve 58 so that no current can be pro- 75

vided to open the valve 58 and thus admit water to the pan 22 unless additional humidity is called for by the humidostat 116.

From the foregoing, it will be apparent that as soon as the humidity in the room reaches the desired maximum, the humidostat 116 operates the relay 118 to break the circuit containing the solenoid controlled valve 58 and thus cuts off the water supply to the evaporator 20. Because of the novel structure of my evaporator, the amount of water in the evaporator pan 22 is very small, even when the water level therein is at a maximum. This means that when the humidostat cuts off the supply of water to the evaporator because the humidity in the room is sufficient, there is only a very slight amount of water in the evaporator which will thereafter be vaporized and this small amount of water will not appreciably increase the humidity in the room after the desired humidity has been reached. This provides a nicety of control which is lacking in the prior art and which is a great improvement thereover.

I have provided my humidifier with a drain pipe 120 to permit draining of the evaporator pan 22 whenever desired. This drain pipe 120 is controlled by a manually operated valve 122 (Figure 11) which can be reached through a door 124 (Figure 1) located at one end of the cabinet 12. The opposite end of the cabinet is provided with a second door 126 (Figure 3) to provide access to the control compartment 36.

In the embodiment of Figures 1 to 8 inclusive, the relay 118 is also in series with the electrical heating coil 44 so that the current supplied to this coil 44 is automatically cut off when humidity in the room reaches the desired maximum. In this embodiment, however, I have provided no means for cutting off the supply of heat to the heating pipes 38, although I appreciate that in some installations the heat supplied to these pipes may be under the control of a thermostat regulating the entire heating system of the building in which the installation is made.

In Figure 9 I have indicated a modification in which the pipe 128 through which steam, hot water, or other heating medium is supplied to the heating pipes 38 is provided with a valve 130 normally closed by a spring 132. The valve 130 is opened by a solenoid 134 under the control of the humidostat 116 and relay 118. In this particular embodiment the heating coil 44 and heating pipes 38 are adapted to be used alternately under the control of the manually operated switch 46.

In the embodiment of Figures 10 and 11 I have illustrated a further modification wherein the heating pipes 38 are provided with inlet and outlet T's 40a and 42a in lieu of the elbows illustrated in Figure 3. The T 40a is connected to a hot water or steam supply pipe 136 and the T 42a is connected to a hot water or steam return pipe 138.

In this embodiment of my invention I have illustrated a heating unit indicated generally by reference numeral 140 as being located above the evaporator 20. The purpose of this heating unit 140 is to heat the air passing through the humidifier and thus heat the room to the desired temperature. A humidifier having such a heating unit may be used to replace the usual radiator.

The heating unit 140 comprises an inlet header 142 connected by the pipe 144 to the T 40a and an outlet header 146 connected by pipe 148 to T 42a. The inlet header 142 is connected by three parallel pipes 150 to a transfer header 152 which communicates with the parallel pipes 154 leading

to the outlet header 146. The pipes 150 and 154 are preferably provided with sheet metal fins 156 to facilitate transfer of heat to the air passing over and around the pipes 150 and 154.

The heating unit 140 is carried on the pipes 144 and 148 and the U-shaped support 158 located beneath the header 152. In Figure 10 I have shown this heating unit 140 as being materially shorter than the evaporator 20 but it is to be understood that the heating unit 140 may be made of any desired and suitable length and provided with any desired number of pipes 150 and 154. The heating unit 140 may also be made of less width than the cabinet 12.

My humidifier is adapted to be connected into the electric lighting circuit of the office or home in which it is located. In the drawings I have illustrated my humidifier as being provided with a conventional flexible electric cord 160 which is detachably connected to the humidifier by the conventional plug and socket connection 162. I have also provided my humidifier with a manually controlled master switch 164.

In the drawings I have illustrated an attractive and desirable shape for my humidifier or combined humidifier and heater. It will be understood, however, that my invention is not limited to the particular shape shown or the details herein illustrated and described as my invention may assume various other forms and shapes. It will be further understood that my invention may be made in various sizes and designs for different purposes and different sizes of rooms, apartments, or buildings to conform to the various needs thereof. It will be also understood that my humidifier may be used to humidify only a single room or a group of rooms or an entire building.

I claim:

1. A humidifier for use in a heating circuit adapted to continue in operation independently of humidity conditions comprising a cabinet for location in a room of a home or office building, an evaporator pan mounted in said cabinet, said evaporator pan having a relatively deep central portion and shallow side portions, means for supplying water to said evaporator pan, heat exchange means substantially filling the deep central portion of said evaporator pan and adapted to be surrounded by water therein, said heat exchange means being connected in the heating circuit and supplied therefrom regardless of the presence or absence of water in said evaporator pan, a float control for cutting off the supply of water to said pan when a predetermined water level obtains in said pan, said level being only slightly above the bottoms of the shallow side portions and providing a thin sheet of water thereover, and a humidostat control for cutting off the supply of water to said pan when a predetermined humidity obtains, said cabinet providing an entrance and exit for air passing over said evaporator pan.

2. A humidifier for use in a heating circuit adapted to continue in operation independently of humidity conditions comprising a cabinet for location in a room of a home or office building, an evaporator pan mounted in said cabinet, said evaporator pan having a relatively deep central portion and shallow side portions, means for supplying water to said evaporator pan, heat exchange means substantially filling the deep central portion of said evaporator pan and adapted to be surrounded by water therein, said heat exchange means being connected in the heating circuit and supplied therefrom regardless of the

presence or absence of water in said evaporator pan, a float control for cutting off the supply of water to said pan when a predetermined water level obtains in said pan, said level being only 5 slightly above the bottoms of the shallow side portions and providing a thin sheet of water thereover, an additional heat exchange means mounted in said cabinet above said evaporator pan, said last-named heat exchange means being 10 connected to said heating circuit and supplied therefrom, and a humidostat control for cutting off the supply of water to said pan when a predetermined humidity obtains, said cabinet providing an entrance and exit for air passing over 15 said evaporator pan and additional heat exchange means.

3. A humidifier for use in a heating circuit adapted to continue in operation independently of humidity conditions comprising a cabinet for 20 location in a room of a home or office building, an evaporator pan mounted in said cabinet, said evaporator pan having a relatively deep central portion and shallow side portions, means for supplying water to said evaporator pan, heat exchange 25 means substantially filling the deep central portion of said evaporator pan and adapted to be surrounded by water therein, said heat exchange means being connected in the heating circuit and supplied therefrom regardless of the 30 presence or absence of water in said evaporator pan, a float control for cutting off the supply of water to said pan when a predetermined water level obtains in said pan, said level being only slightly above the bottoms of the shallow side 35 portions and providing a thin sheet of water thereover, an electric heater mounted in said evaporator pan, and a humidostat control for cutting off the supply of water to said pan and the current to said electric heater when a predetermined 40 humidity obtains, said cabinet providing an entrance and exit for air passing over said evaporator pan.

4. A humidifier for use in a heating circuit adapted to continue in operation independently 45 of humidity conditions comprising a cabinet for location in a room of a home or office building, an evaporator pan mounted in said cabinet, said evaporator pan having a relatively deep central

portion and shallow side portions, means for supplying water to said evaporator pan, heat exchange means substantially filling the deep central portion of said evaporator pan and adapted to be surrounded by water therein, said heat exchange means being connected in the heating circuit and supplied therefrom regardless of the presence or absence of water in said evaporator pan, a float control for cutting off the supply of water to said pan when a predetermined water 10 level obtains in said pan, said level being only slightly above the bottoms of the shallow side portions and providing a thin sheet of water thereover, a filler of high heat conductivity for 15 said pan, said filler having interstices adapted to be filled by water in said pan, and a humidostat control for cutting off the supply of water to said pan when a predetermined humidity obtains, said cabinet providing an entrance and exit 20 for air passing over said evaporator pan.

5. A humidifier for use in a heating circuit adapted to continue in operation independently of humidity conditions comprising a cabinet for location in a room of a home or office building, an evaporator pan mounted in said cabinet, said 25 evaporator pan having a relatively deep central portion and shallow side portions, means for supplying water to said evaporator pan, heat exchange means substantially filling the deep central portion of said evaporator pan and adapted 30 to be surrounded by water therein, said heat exchange means being connected in the heating circuit and supplied therefrom regardless of the presence or absence of water in said evaporator pan, a float control for cutting off the supply of 35 water to said pan when a predetermined water level obtains in said pan, said level being only slightly above the bottoms of the shallow side portions and providing a thin sheet of water thereover, emergency control means for cutting 40 off the supply of water to said pan upon failure of said float control, and a humidostat control for cutting off the supply of water to said pan when a predetermined humidity obtains, said cabinet providing an entrance and exit for air 45 passing over said evaporator pan.

FRED W. STILWELL.
